Application October 9, 1935, Serial No. 44,176

5 Claims. (Cl. 137—69)

The present invention relates generally to devices for preventing back siphonage of water into water supply lines. The invention is applicable to water supply line outlets generally, though it is of particular advantage and importance in connection with flush valves, and will accordingly be herein specifically described and illustrated in that typical service, but without necessary limitation thereto.

10 It is known that under certain conditions, water may be sucked backwardly through a water outlet into the water supply line. This is generally due to exhaustion of water in the mains, or reduction of pressure in the mains or in the line that supplies the outlet. Assuming the outlet to be connected to a flush valve installed in connection with a toilet bowl, the valve normally being held closed by the pressure in the water line, it will be seen that reduction of pressure in 15 the mains may cause an actual suction in the water supply line, and this may cause the flush valve to open, allowing the suction to continue on down into the toilet bowl, and in some instances may lift the water out of the bowl into 20 the water line. It will further be evident that a similar occurrence is possible in various situations not involving flush valves; for example, it is possible for back siphonage to occur in any situation in which the water outlet has access to 25 the water which it has discharged, as in the instance of a swimming pool supplied by way of outlets located beneath the water level.

It is a primary object of the present invention to provide simple and effective means for positively preventing such back siphonage of water 30 into the supply line.

Taking the flush valve situation for illustration, the device of the present invention involves a tubular body formed with a liquid passage and 35 placed between the flush valve and the toilet fixture. An air admission passageway opens within this body, and a check valve is provided which is adapted to move onto a lower seat to cover this passageway during flushing discharge. 40 Upon development of suction in the line and valve, air is admitted through this air passageway, thereby breaking the siphon action and so preventing lifting of water from the bowl, and the check valve lifts onto an upper seat to establish 45 a barrier between the toilet fixture and the flush valve water line. In a preferred construction, this check valve is normally supported by a spring in a position near the described upper seat. Once the valve is tightly onto its upper seat, admission of air is of course interrupted, but

seating of the check valve then prevents lifting of water or gases past that point. If, however, the check valve does not tightly fit its upper seat, due for instance to wear, then air which is sucked in through the admission passage escapes upwardly past the check valve, but in so doing breaks the suction or siphon action, and prevents lifting of water from the toilet bowl. When the suction in the line ceases, the check valve is supported by the aforementioned spring, the arrangement being such that the check valve is moved onto its lower seat to close the air inlet immediately upon flushing discharge. The advantage of this spring is that the device is made sensitive to lighter suction in the line.

The invention will be better understood from the following detailed description of a present preferred embodiment thereof applied to a typical flush valve, reference being had to the accompanying drawings, in which:

Fig. 1 is a vertical medial section of the device of the present invention installed in connection with a typical and preferred flush valve, the flush valve and siphon breaking device being shown in normal closed position;

Fig. 2 is a view similar to that of Fig. 1, but showing the flush valve and siphon breaking device in operating position upon development of suction in the water line;

Fig. 3 is a section taken on line 3—3 of Fig. 1; 30

Fig. 4 is a section taken on line 4—4 of Fig. 1;

Fig. 5 is a section taken on line 5—5 of Fig. 2; 35

Fig. 6 is a view similar to a portion of Fig. 1, but showing a modification.

While I here describe and illustrate a typical and preferred flush valve in connection with the device of the present invention, it is to be understood that such typification constitutes no implied limitation on the use of the present invention, which is applicable to flush valves generally, as well as to other water outlets. However, for the purpose of completely explaining the device of the present invention, especially in its association with flush valves, I describe in some detail a 40 preferred flush valve. It may here be stated that the illustrated flush valve per se is the subject matter of my copending application entitled Flushometer, filed August 5, 1933, Ser. No. 683,807, now Patent No. 2,066,086, of Dec. 29, 1936. 45

The illustrative flush valve will first be described. Numeral 10 designates a tubular flush valve body member, to the bore 11 of which opens laterally extending inlet 12 arranged for threaded attachment at 13 to a supply line (not shown). 50

The downwardly opening outlet of the valve is indicated at 14, and is exteriorly threaded at 15 for connection with the fixture below. The upper end of body 10 is closed by a cap 16.

5 Formed within body 10, concentrically with reference to its bore 11, is an upstanding annular flange or discharge pipe 17 which is spaced annularly from the outer wall of the body member. The upper end 19 of this flange provides a sealing 10 face, as will later be explained. It may here be mentioned that the main fluid passage through the valve extends from inlet 12 over the upper end of flange 17 and through its bore 20 to outlet 14.

15 A valve assembly V is movable vertically through bore 11 of the body member to and from a position of sealing engagement against flange end 19. This assembly V includes a body portion 21 of cup-shaped configuration, to the lower end 20 of which is screwthreaded a depending sleeve 23 of the main valve, said sleeve having sliding fit over flange 17, leaving the bore of said flange unobstructed. The lower end of body portion 21 carries a seating ring 25, of rubber or the like, 25 which is adapted to engage flange end 19 in fluid-tight relation when the main valve is closed, as in Fig. 1.

Vertically extending liquid passageways or channels 28 are sunk in the inner face of sleeve 30 23.

Screwed to the upper end of valve body portion 21 is a valve head 31, cup leathers 33 and 34 being clamped between body portion 21 and head 31. The cylinder chamber above the piston, which 35 is generally designated at 36, is indicated at B, while the cylinder chamber below piston 36 is indicated at A. Valve body portion 21 and head 31 define a piston chamber H. An orifice 37 in body portion 21 maintains compartment H in constant communication with the liquid inlet. A liquid passageway 38, 39 extends through head 31 from chamber H.

The bottom wall 41 of body portion 21 has a central opening 48 which is normally adapted to 45 be closed by the relief tilt-valve generally indicated at 49. This valve embodies a circular head 50 normally adapted to seat in fluid-tight engagement on seat-ring 52, of rubber or the like, which ring is mounted on wall 41 concentrically with 50 respect to opening 48. Head 50 has a conical extension 54 which takes and centers the lower end of compression spring 55, the upper end of which bears against head 31. This spring has a constant tendency to urge valve 49 to closed position.

55 Depending from head 50 is a stem 57 which extends with annular clearance through orifice 48, and thence on downwardly through bore 20 of flange 17. The lower end of the stem tapers 60 downwardly at 58 and terminates in a tip 59 of materially reduced diameter. A spring retainer clip 60 is utilized in connection with stem 57. This clip comprises an arcuate body portion 61 (see Figs. 1 and 5) which is sprung into the 65 groove 62 cut in body member 10 at a point below the base of discharge flange 17. The two arms or ends of the retaining member are struck back convergently at 64 and 65 forming a convergent guide-passageway to restricted throat 66, smaller 70 than the major outside diameter of stem 57, the retainer being positioned so stem 57 lines opposite throat 66. The tips 67 and 68 of the retainer are struck reversely to form a diverging guide channel 73, for a purpose to be explained later.

75 The tilt valve actuator is generally designated

at 74, and includes a plunger 75 having sliding fit through bore 76 which is located to bring the end of the plunger directly in line with stem 57. The outer end of rod 75 carries a head 77 which is confined for horizontal sliding movement 5 through the bore of bonnet nut 78 threaded to body member 10, as shown. The end of nut 78 is turned over at 78a to confine the flange 80 of actuating handle 81. A compression spring 84 encircles rod 75 and bears at its opposite ends 10 against head 77 and packing follower 83. In the full line position of Fig. 1, handle 81 is in "at rest" position. To operate the valve, handle 81 is rocked in any direction (such as downwardly to the dotted line position of Fig. 1) which results in rod 75 being thrust to the left, engaging valve stem 57 and swinging the tilt-valve to open position, as indicated in dotted lines in Fig. 1.

In describing the operation of the flush valve, it will first be assumed that it is in the full line 20 position of Fig. 1, fluid under supply pressure standing in chambers A, B, and H, the fluid in chamber B having been admitted through orifice 37, chamber H and passageway 38, 39. Since the upwardly exposed effective pressure area of the 25 piston is greater than the downwardly exposed effective pressure area, the assembly V is held down in the position of Fig. 1, thus effecting a barrier between inlet 12 and outlet 14. When handle 81 is rocked, thrust rod 75 is moved inwardly, its end engaging stem 57 and thus tilting valve 49 to the dotted line position of Fig. 1. This movement of stem 57 spreads retainer arms 64 and 65 to pass the stem through throat 13 into the dotted line position of Fig. 5, the retainer arms then springing back to hold said stem releasably in its position of angularity, and thus releasably maintaining the valve in tilted or open position. The tilt valve is thus retained in open or tilted position, though handle 81 may 40 be immediately released and allowed to return to its normal at rest position.

With valve 49 thus open, the pressure in chamber B is relieved, the fluid therefrom passing downwardly through passageway 39, 38, chamber 45 H, orifice 48, bore 20, and thence outwardly through discharge opening 14. As the pressure in chamber B is thus relieved, the consequent predominant pressure in chamber A moves valve assembly V upwardly from the position of Fig. 1. 50 In moving upwardly from the position of Fig. 1, valve assembly V is unseated from the upper end 19 of flange 17, whereupon fluid is free to flow from inlet 12 under the lower end of sleeve 23, thence upwardly through passageways 28, and 55 then over end 19 of flange 17, and downwardly through bore 20 through discharge outlet 14, this constituting the main fluid passage through the valve.

Tilt valve 49 in open position, is carried upwardly with the vertically rising valve assembly V in its upward movement from the closed position of Fig. 1, stem 57 being drawn upwardly through but not laterally freed from retainer 60. The effective length of stem 57 is such that as 65 the valve assembly reaches a predetermined position the major diameter portion of said stem is lifted clear of arms 64 and 65, whereupon stem 57 is free to swing back to normal position, closing release valve 49.

70 With the return of valve 49 to closed position, flow through orifice 48 is interrupted, and supply line pressure admitted to chamber H through orifice 37 restores the pressure in chamber B through passageway 38, 39. Due to the greater 75

effective area exposed to the pressure in chamber B, valve assembly V is thereupon moved downwardly to closing position (Fig. 1).

The siphon breaker comprises a hollow tubular body 90 provided at its upper end with an internally threaded inlet portion 91 adapted to be screwthreaded to flush valve outlet 14. The lower end of body 90 is provided with a downwardly opening outlet portion 92, which is externally threaded at 93 for threaded connection with a collar 94 which tightens a packing 95 on the flushing line 96 received within outlet 92, and which leads to the toilet fixture, not shown.

Cast integrally with body 90 is a horizontal transverse air passage tube 98, the two ends of which open through the side walls of body 90, and are covered over or protected by depending lips 99, which form downwardly opening air inlet ports 100 communicating with the open ends of tube 98. A vertical tube 102 is cast integrally with the top side of horizontal tube 98, and extends upwardly concentrically with reference to tubular body 90. The upper end 103 of this tube 102 terminates somewhat short of the base of the screwthreaded inlet portion 91 of the body, as shown.

A check valve, generally designated at 106, is mounted on the upper end 103 of vertical tube 102 (Fig. 1), and is adapted to lift from such position under certain conditions, as will later be explained. This check valve 106, which is formed of "Bakelite," or any other material found suitable, comprises a head 107, the underside of which is formed with a flat surface 108 adapted to seat in fluid tight engagement on the upper end 103 of tube 102. Head 107 is formed with a depending collar or annular flange 110 annularly spaced from tube 102. The bore of this collar is formed with vertical ribs 111 which slidably fit tube 102, and provide vertical air passages 112 leading from the upper end of tube 102 (when valve 106 is lifted) downwardly through collar 110 and into the hollow body 90.

Valve head 107 is formed with an outwardly extending annular flange 115, which presents an upwardly facing annular seating surface 116 adapted to seat on the downwardly facing annular seating surface 117 of a seat ring 118 screwthreaded within inlet 91. Check valve 106 is shown so seated against ring 118 in Fig. 2.

Seat ring 118 is positioned by engagement with an inwardly extending annular flange 120 formed in body 90 at the base of threaded inlet 91. Preferably, a sealing washer 121, of rubber or similar material, is placed on the upper side of seat ring 118 and is engaged and compressed by the lower end of flush valve outlet 14, when the flush valve and siphon-breaker are connected.

The normal at rest condition of the flush valve and siphon breaker is as shown in full lines in Fig. 1. The valve assembly of the flush valve is held closed by line pressure, in the manner previously explained, and check valve 106 rests downwardly on the upper end of tube 102 by the force of gravity. Valve 106 being thus seated on tube 103, the air passageway consisting of ports 100, horizontal tube 98 and vertical tube 102 is sealed off, and escape of water therethrough is prevented during normal downward discharge of water from the flush valve.

Now, in the event of suction in the water supply line connected to flush valve inlet 12, the downward pressure of the water on piston assembly V may become reduced to the point that atmospheric pressure below will cause said assembly to rise, as to the open position shown in

Fig. 2, thus opening the main fluid passageway, designated by arrows M, and consisting of bore 20 of flange 17, grooves 28 in depending flange 23, and inlet 12, thus allowing the suction to extend down to and within the hollow body of the siphon breaker. This suction causes air to be drawn inwardly through ports 100, tubes 98 and 102, and grooves 112, as indicated in Fig. 2 by arrows S, check valve 106 being caused to lift and to seat upwardly against seat ring 118, as illustrated in Fig. 2. The air so sucked within body 90 supplies the suction from above and so breaks the siphon action, preventing the lift of water from the bowl. Engagement of check valve 106 with seat ring 118 then establishes a positive barrier in the line, effectually preventing any possible rise of water or gases past said point. If, however, the cooperating seating faces of check valve 106 and seat ring 118 should become worn or marred so as to prevent a water-tight fit, thereby holding the check valve slightly open, the air which is being sucked inwardly through ports 100 and tubes 98 and 102 will escape upwardly past the check valve, but in so doing will act to break the siphon action, preventing lift of water from below.

The air admitted by way of ports 100 and tubes 98 and 102 is sucked into the water line with very much less force than would be required to lift the water from the bowl. Consequently, the force applied by the suction is exhausted in sucking the air inwardly through said passageway, and the suction is thereby reduced to such a degree that lifting of the water from below becomes impossible.

It will be evident that the check valve of the device has a triple function, i. e., first, as a positive check valve which is closed by the force of the air sucked inwardly through the air admission passageway, second, as a siphon breaker by virtue of its action in admitting air into the line, and third, as a valve for closing the air admission passageway during flushing discharge.

The device is simple in construction, involving but one moving part. It is trustworthy in operation, and even after long service, with consequent wear, effectively safeguards against the possibility of back-siphonage of water into the supply line.

Fig. 6 shows a modification, in which a comparatively light spring 130 is placed around check valve collar 110, and vertical tube 102, seating downwardly against horizontal tube 98, and serving to hold the check valve normally nearly closed on its seat 117. The spring is sufficiently flexible that discharge of water from the valve, when it is flushing, compresses the spring instantly to the point where the underface 108 of the check valve seats on the upper end 103 of vertical air passage tube 102, thereby assuring against discharge of water outwardly through the air ports. Employment of this spring is of advantage, in that lighter suction in the line will lift the check valve to closed position. This spring is useful in some installations, in situations wherein the slightest line suction is to be guarded against.

As previously stated, the siphon breaker of the present invention is not limited in applicability to its combination with a flush valve, but may be installed in connection with any water outlet where there is danger of water being sucked backwardly due to reduction of pressure in the mains. In any such instance the siphon breaker is simply installed in the water line ahead of the final water outlet, as will be obvious.

While I have now described certain specific means illustrative of the invention, it is to be understood that various changes in design and structure may be made in the illustrative embodiment without departing from the spirit and scope 5 of the invention as defined in the appended claims.

I claim:

1. In a device of the character described, the combination of a body having an inlet at its upper end, an outlet at its lower end, and a vertical fluid passageway from inlet to outlet, an air inlet passageway in the body terminating in an orifice opening upwardly within the fluid passageway, an upwardly facing valve seat around said orifice, a check valve disk within the fluid passage adapted 10 to seat downwardly on said valve seat, a downwardly facing valve seat within the body disposed around the fluid passageway, said valve disk being adapted to be moved upwardly from its upwardly facing seat to seat against said downwardly facing seat, and a spring yieldingly supporting said check valve disk normally in a position near said downwardly facing seat, said valve disk being movable onto said second seat 15 by virtue of suction applied to the inlet and consequent admission of air through the air inlet passageway, and being held in its first mentioned position by flow of water through the fluid passageway from inlet to outlet.
2. In a device of the character described, the combination of a body having an inlet at its upper end, an outlet at its lower end, and a vertical fluid passageway from inlet to outlet, means forming an air inlet passageway in the body, said means terminating within the fluid passageway in a vertical tube having an upwardly facing outlet orifice, a check valve disk within the fluid passage adapted to seat downwardly on the upper 20 end of said tube, a downwardly facing valve seat within the body disposed around the fluid passageway, said valve disk being adapted to be moved from the upper end of said vertical tube to seat against said downwardly facing seat by virtue of suction applied to the inlet and admission of air through said air inlet passageway, and a spring yieldingly supporting said check valve disk normally in a position near said downwardly facing seat.
3. In a device of the character described, the combination of a body having an inlet at its upper end, an outlet at its lower end, and a vertical fluid passageway from inlet to outlet, means forming an air inlet passageway in the body, said means terminating within the passageway in a vertical tube having an upwardly facing outlet

orifice, a check valve within the fluid passageway comprising a disk adapted to seat downwardly on the upper end of said tube, a depending collar on said valve disk spaced from said vertical tube, a downwardly facing valve seat within the body disposed around the fluid passageway, said valve disk being movable from the upper end of said vertical seat against said downwardly facing seat, and a spring yieldingly supporting said check valve disk normally in a position near said downwardly facing seat.

4. In a device of the character described, the combination of a body having an inlet at its upper end, an outlet at its lower end, and a vertical fluid passageway from inlet to outlet, means forming an air inlet passageway in the body, said means terminating within the fluid passageway in a vertical tube having an upwardly facing outlet orifice, a check valve within the fluid passageway comprising a disk adapted to seat downwardly on the upper end of said tube, a depending collar on said valve disk annularly spaced from said vertical tube, vertical ribs within said collar having a loose sliding fit on said vertical tube, a downwardly facing valve seat within the body disposed around the fluid passageway, said valve disk being movable from the upper end of said vertical tube to seat against said downwardly facing seat, and a spring yieldingly supporting said check valve disk normally in a position near said downwardly facing seat.

5. In combination, a liquid supply line, a liquid discharge line, and a siphon breaker between said supply line and discharge line comprising a tubular body forming a liquid passageway and having an air inlet passageway terminating in an orifice opening within said liquid passageway, a valve seat around said orifice, a check valve member in the liquid passageway movable onto said seat, and a valve seat in the body around the liquid passageway located between said first mentioned seat and the fluid inlet and providing a second seat for the check valve member, a spring yieldingly supporting said check valve member normally in a position near said second mentioned seat, said check valve member being moved onto the first mentioned seat against said spring by flow of water through the tubular body from the supply line, and being adapted to be moved onto said second mentioned seat by virtue of development of suction in the line and consequent admission of air through the air inlet passageway, so as to close the tubular body and so prevent back flow of liquid into the line.

ELIHU C. WILSON.
